UNITED STATES PATENT OFFICE.

WILLIAM J. HAGMAN, OF PHILADELPHIA, PENNSYLVANIA.

EAT-RETAINING SYSTEM FOR ENGINES.

1,128,133.

Specification of Letters Patent.

Patented Feb. 9, 1915.

Application filed February 13, 1914. Serial No. 818,536.

To all whom it may concern:

Be it known that I, WILLIAM J. HAGMAN, a citizen of the United States, residing in Philadelphia, Pennsylvania, have invented 5 certain Improvements in Heat-Retaining Systems for Engines, of which the following is a specification.

One object of my invention is to provide a combination of apparatus primarily 10 arranged to store the hot liquid employed in the cooling system of an internal combustion engine, so that it shall be available for use in warming such engine when it is again desired to put it into use after a 15 more or less prolonged period of idleness.

I further desire to provide a liquid storage system in connection with the cooling system of an internal combustion engine, together with means whereby the flow of 20 liquid between the two systems may be conveniently controlled at will, the arrangement of parts being relatively simple, substantial and of such a nature as to require but a minimum of attention.

25 These objects and other advantageous ends I secure as hereinafter set forth, reference being had to the accompanying drawings, in which:

Figure 1 is an elevation, partly in section and to some extent diagrammatic, showing my invention as applied to an internal combustion engine; Fig. 2 is a full size vertical section illustrating the detail construction of one of the valves and its associated parts; Fig. 3 is a vertical section of 35 another valve preferably forming part of the invention, and Fig. 4 is a transverse section on the line *a—a* Fig. 3.

In the above drawings, 1 and 1^a represent 40 the cylinders of an internal combustion engine, which is shown as mounted on a motor vehicle whose body is indicated at 2 and said engine is provided with a radiator 3 whose upper part is connected through a 45 pipe 4 with the water jackets 5. These latter are also connected through a manifold 6 with a pipe 7 leading to the outlet of a pump 8 whose inlet pipe 9 is connected to the bottom of the radiator 3. If desired, 50 I may connect the carburetor, indicated in dotted lines at 10, to the water system through pipes 11 and 12, of which the first leads from the pipe 9 and the second is connected into one of the water jackets 5.

55 In addition to the above apparatus, which constitutes a well known form of cooling

system, I provide a reservoir 13 mounted inside of a containing casing 14, from whose walls it is effectually insulated to prevent heat conduction thereto, by means of a packing of any suitable insulating material 15, although, if desired, the space between the walls of the reservoir 13 and those of the casing 14 may be hollow and exhausted of air in order to attain the same end. Immediately adjacent the casing 14 and preferably connected thereto, I provide a tank 16 for compressed air, which may be connected through a pipe 17 to any suitable source of the same, such, for example, as a pump (not shown). Said casing 14 with its tank is preferably, though not necessarily, located at some point below the water jackets 5 and the other liquid containing apparatus constituting the cooling system of the engine, and its lowest portion is connected to the pipe 7 thereof through the pipe 18 including a valve or cock 19, preferably of the detail construction shown in Fig. 3. The movable member 19 of this valve, which is connected to a handle 20, may be so adjusted as to permit free flow of liquid between the two parts of the pipe 18 with which it is connected, or it may be so turned as to connect that part of said pipe leading to the pipe 7 with a discharge opening 21 in its casing. Again, it may be so turned as to close this latter opening and cut off communication between the main part of the pipe 18 and the reservoir.

The upper part of the air tank 16 is connected to the upper part of the insulated reservoir 13 by a pipe 22 and a valve casing 23, in the latter of which there is mounted a check valve 24 normally held closed by a spring 25. Said valve is so arranged as to also be forced toward its seat by the air pressure from the tank 16, and in order to unseat it for the purpose of permitting flow of air through the pipe 22 and casing 23 to the reservoir 13, I provide a threaded plug 26 having a substantially cylindrical end 27 closely fitting a cavity in said casing 23 into which the stem of the valve 24 projects and which also opens into the passage 28 leading to said reservoir.

By unscrewing the plug 26, either by hand or by the use of a suitable wrench or handle, this closely fitting end 27 may be made to cover an outlet opening 29 and thus permit escape of air from the reservoir 13 through

the passage 28 in the valve casing 23. On the other hand, if sufficiently screwed into the cavity of the casing, the end 27 of this plug 26 completely cuts off the outlet opening 29 and ultimately engages the stem of the valve 24 so as to unseat the same.

When the engine to which my invention is attached has been in operation for a more or less prolonged time, the water in its cooling system is heated to a considerable degree, and when said engine is to be shut down for some time, particularly in cold weather, the handle 20 of the cock 19 is so turned as to establish communication between the two parts of the pipe 18 and thus permit the greater part of the liquid to pass into the reservoir 13, which, being effectually insulated as above described, maintains it in a hot condition with relatively little reduction in temperature for a prolonged period of time. After this discharge of liquid from the system, the handle 20 is so manipulated that the movable element of the cock completely closes off communication with the reservoir 13, and puts the body of the pipe 18 in connection with the outlet port 21, thus permitting escape of that part of the cooling liquid which still remains in said pipe.

While I have shown that pipe 7 as entering the top of the pump 8, so that a small quantity of liquid would be trapped therein and in the pipe 9 and bottom of the radiator 6, obviously the connection may be made at such a point of the system that absolutely all of the liquid will be drawn off into the reservoir 13. In order to permit flow of the liquid from the engine to the reservoir 13, the air is allowed to escape therefrom by unscrewing the plug 26 far enough to uncover the passage 29, after which the latter is closed by screwing in the plug. When it is desired to again start the engine, the handle 20 of the cock 19 is first brought to a position in which communication is established between the two parts of the pipe 18, and the air tank 16 being filled with air under pressure, the plug 26 is screwed inwardly until by engaging the stem 23 of the valve 24, it unseats the latter, thus allowing air to flow into the reservoir 13 and forcing the still hot liquid therefrom back in the engine, radiator and their connections. At any time, and particularly in cold weather, the effect of this warm liquid is to heat the cylinders of the engine together with their associated parts, so that no trouble is experienced in starting, where ordinarily such operation would be extremely difficult after the engine had been allowed to cool by standing idle even for a short time. When all or a sufficient quantity of the liquid has been forced out of the reservoir 13, the handle 20 of the cock 19 is so turned as to again cut off communication between the main part of

the pipe 18 and the short section leading to the reservoir, after which the plug 26 may be unscrewed sufficiently to allow the valve 24 to seat.

While I preferably mount the reservoir 13 so that the hot liquid from the engine cooling system will run into it by gravity, it is obvious that it may be placed on a level with or above the engine, without departing from my invention, suitable means being provided for causing the liquid to flow to and from the insulated storage reservoir. In any case, however, the work of starting the engine in cold weather is made relatively easy, since the heat retained in the cooling water by the insulated reservoir is utilized to warm the engine cylinders and other parts, so that no trouble is experienced in causing ignition and combustion of fuel charges when said engine is put into operation.

I claim:

1. The combination of an internal combustion engine having a water jacket; a radiator connected to said water jacket; a body of liquid in the radiator and water jacket for cooling the engine; an insulated reservoir connected to receive hot liquid from both the radiator and engine when the latter is shut down; and means for causing the liquid to return to the engine and radiator from the reservoir when it is desired to start the engine.

2. The combination of an internal combustion engine; a system of apparatus including a body of liquid for cooling said engine during its operation; means external to the engine for storing said liquid and preventing substantial loss of heat therefrom while the engine is shut down; and means for thereafter returning said heated liquid to the engine and to the cooling system when it is desired to start said engine.

3. The combination of an engine having a water jacket; a cooling system connected to said water jacket; a body of liquid in said system; an insulated reservoir connected to said cooling system; with means including a source of a gas under pressure for controlling the flow of liquid between said reservoir and the system at will.

4. The combination of an engine having a water jacket; a radiator connected thereto; a body of cooling liquid; means for circulating said liquid through the engine and radiator; an insulated reservoir connected to receive liquid from the engine and radiator; an air tank communicating with said reservoir; a valve for controlling the flow of air from the tank to the reservoir; and a second valve for controlling the flow of liquid between the reservoir and the engine.

5. The combination of an engine having a water jacket; a cooling system; a body of liquid in said system; an insulated reservoir; a pipe connecting said reservoir with

the cooling system; a valve in said pipe; a gas containing tank connected to the reservoir; and means for establishing communication between the reservoir and the atmosphere or between the reservoir and the gas tank.

6. The combination of an internal combustion engine; a system of apparatus including a body of liquid for cooling said engine during its operation; means external to engine and cooling system for storing the said liquid and preventing substantial loss

of heat therefrom while the engine is shut down; and a source of power external to the engine, other than gravity, for forcing 15 said liquid from the engine and cooling system to the storage system.

In testimony whereof, I have signed my name to this specification, in the presence of two subscribing witnesses.

WILLIAM J. HAGMAN.
